CRYSTAL HOLDER

George L. Usselman, Port Jefferson, and Ralph E. Franklin, Patchogue, N. Y., assignors to Radio Corporation of America, a corporation of Delaware

Application November 16, 1937, Serial No. 174,768

11 Claims. (Cl. 171—327)

This invention relates to a novel and improved piezo-electric crystal holder and deals more specifically with the insulation and spacing of the electrodes in a crystal housing having a fixed air gap between the crystal and the electrodes.

5 An object of this invention is to simplify and improve piezo-electric crystal holders to reduce the cost and maintenance thereof.

Another object of this invention is to provide 10 a piezo-electric crystal holder in which the insulation and spacing material for the electrodes is so chosen as to have substantially the same coefficient of linear expansion as the average value of the crystalline quartz element.

15 A feature of this invention is the use of a multi-electrode holder comprising a single crystal and at least four electrodes, which holder is particularly useful in a push-pull circuit.

Another feature of this invention is that the 20 insulation, electrodes and spacers determining the air gap are so chosen as to give the least change in gap capacity of the crystal holder for a given change in holder temperature.

25 Piezo-electric crystals are generally old in the art; however, the recent trend in the piezo-electric crystal art has been toward crystals with a low or zero temperature coefficient of frequency; by the use of such crystals, temperature control devices are either eliminated or reduced to poor 30 temperature control thus materially reducing the cost. In crystal holders of the fixed gap type, one of the reasons for changing frequency with changing temperature is the change in the gap capacity due to unequal expansion or contraction 35 of the quartz, electrodes, insulation and spacing member.

35 Crystal holders known in the prior art are usually made with such material as porcelain or Bakelite insulation and electrodes of brass or copper; for the material in this invention, nickel or Monel metal electrodes are preferably used as these metals have a coefficient of expansion very close to the crystalline quartz crystal. Also, for the insulation material, we prefer to use glass insulation having a characteristic similar to that of quartz; therefore, the insulating spacers of this improved crystal holder are preferably made of glass or fused quartz, depending upon the characteristics desired.

45 The present invention may best be understood and described by referring to the accompanying drawing, in which:

Fig. 1 is a side elevation of an improved crystal holder having glass end support members;

Fig. 1a is an end view of Fig. 1;

Fig. 1b is a detail section showing the method of supporting the electrodes to the glass end support members;

Fig. 2 is a side view of a crystal holder having insulating support plates upon which the crystal 5 and electrodes are supported;

Fig. 2a is an end view of Fig. 2;

Fig. 3 is a front view of another modification similar to that of Fig. 1; and

Fig. 3a is an end view of Fig. 3.

50 Referring now in detail to Fig. 1 of the drawing, four metal electrodes #1, 2, 3 and 4 are shown which are made of Monel or nickel metal which has substantially the same similar coefficient of expansion as that of the quartz; or, they 55 may be made of some other metal with a slightly different coefficient of expansion, which will give a desired expansion characteristic. The electrodes are supported by glass end support members 5, 6, 7 and 8 which are arranged to give the proper air gap, for the crystal in use, and are also cut to allow a minimum motion of the quartz crystal 9 while it is in operation. A single piece copper shield 10 is attached to the insulating end members by means of terminals 11 and binding screws 12; this shield is particularly desirable for shielding between grid and plate electrodes of certain crystal circuits. In order to keep the air gap constant, the metallic members not employed as electrodes are kept to a minimum; therefore, the electrode binding screws 13 and 14 are also employed to make the electrical connections by being fastened to lugs 15, 16, 17 and 18.

55 The lower portions of electrodes 1, 2, 3 and 4 are fastened by means of screws 19, as shown in Fig. 1b. The adjacent screws are countersunk to a sufficient depth to prevent short circuiting between the two electrodes. The lower insulating support members 7 and 8 are provided with projections 20 and 21 to keep the crystal from slipping out of place. The overhanging portion of copper shield 10 may, if desired, be used for attaching the holder to any suitable support (not shown).

60 Fig. 2 shows a pair of insulating support plates 30 and 31 upon which four metallic electrodes 32, 33, 34 and 35 are mounted. A piezo-electric crystal 36 is spaced from the electrodes by means of four glass or quartz tube spacing members 37, which like the end supports 5, 6, 7 and 8 are arranged to give the proper air gap for the crystal in use, and also are cut with a groove to allow a minimum motion of the quartz crystal 9 while it is in operation. The plates 30 and 31 are spaced by members 37 and bound together by means of 65

four screws 38 and nuts 39. The electrodes are symmetrically arranged upon insulating plates 30 and 31 by means of a plurality of screws 40. In order to keep the amount of metal to a minimum, electrical connections are made to the electrodes by means of soldering lead wires 41, into the apertures 42.

Fig. 3 is a modification similar to that of Fig. 1, except that it combines certain of the features of Fig. 2 in that the crystal spacing between the electrodes is maintained by means of spacing tubes 50, one of which is provided to space apart the top end support members 51 and 52 and three spacing members 50 are provided for the lower end supports 53 and 54, the electrodes 55, 56, 57 and 58 being secured to end members 51 to 54, inclusive, by means of a plurality of screws 59. The electrical connections are made similar to that of Fig. 2 in that a lead 60 is soldered in the end portion of the electrodes.

Figs. 2 and 3 show other suggested variations from those of Fig. 1 to allow greater freedom in selection of materials for the characteristics desired.

Figs. 1 and 3 show types in which there is no plane of symmetry of the electrodes perpendicular to the plane of the crystal which shows the type in which the electrodes are symmetrically arranged, and while only three modifications of this invention are shown, it is to be distinctly understood that it is capable of taking other forms.

What is claimed is:

1. A piezo-electric crystal holder having an air gap comprising a piezo-electric crystal, insulating members located at the ends of said crystal, and metallic electrodes adjacent each face of said crystal and secured to said insulating members.

2. A piezo-electric crystal holder having a fixed air gap comprising a piezo-electric crystal, a pair of insulating members located at one end of said crystal, and two metallic electrode members located at each face of said crystal, said metallic end members being secured to said insulating members.

3. A piezo-electric crystal holder having a fixed air gap comprising a piezo-electric crystal, a pair of insulating members located at one end of said crystal, and two metallic electrode members located at each face of said crystal, said metallic end members being secured to said insulating members, the area of said electrodes being substantially less than the area of said crystal.

4. A piezo-electric crystal holder having a fixed air gap comprising a piezo-electric crystal, a pair of insulating members located at one end of said crystal, and two metallic electrode members located at each face of said crystal, said metallic end members being secured to said insulating members, the area of said electrodes being substantially less than the area of said crystal, and a metallic shield located between said electrodes.

5. A piezo-electric crystal holder having a fixed air gap comprising a piezo-electric crystal, glass spacing members located at the ends of said crystal, and metallic electrodes adjacent each face of said crystal and secured to said spacing members.

6. A piezo-electric crystal holder having a fixed air gap comprising a piezo-electric crystal, a plate of insulating material of greater area than said crystal for supporting and spacing said crystal, and metallic electrodes adjacent each face of said crystal and secured to said insulating plate.

7. A piezo-electric crystal holder having a fixed air gap comprising a piezo-electric crystal, a plate of insulating material of greater area than said crystal for supporting and spacing said crystal, and two metallic electrodes adjacent each face of said crystal and secured to said insulating plate.

8. A piezo-electric crystal holder having a fixed air gap comprising a piezo-electric crystal, a plate of insulating material of greater area than said crystal for supporting and spacing said crystal, and unsymmetrically arranged metallic electrodes adjacent each face of said crystal and secured to said insulating plate.

9. A piezo-electric crystal holder having an air gap, comprising a quartz piezo-electric crystal, insulating material for supporting and spacing said crystal, metallic electrodes adjacent each face of said crystal and secured to said insulating material, the material of said insulation and said metallic electrodes being so chosen so as to have an expansion characteristic similar to said quartz piezo-electric crystal to give a minimum change in gap capacity for a definite change in the crystal holder temperature.

10. A piezo-electric crystal holder having a fixed air gap comprising a piezo-electric crystal, a pair of insulating plates having a greater area than said crystal for supporting said crystal, a plurality of metallic electrodes adjacent each face of said crystal and secured to said insulating plates, a plurality of insulating tubes interposed between said pair of insulating plates for spacing said crystal from said electrodes, and binding means for securing said insulating plates and tubes together.

11. A piezo-electric crystal holder having a fixed air gap comprising a piezo-electric crystal, a pair of insulating plates having a greater area than said crystal for supporting said crystal, two metallic electrodes adjacent each face of said crystal and secured to said insulating plates, a plurality of glass tubes interposed between said pair of insulating plates for spacing said crystal from said electrodes, and binding means for securing said insulating plates and tubes together.
